UNITED STATES PATENT OFFICE.

JOHN LIPINSKI, OF LEAVENWORTH, KANSAS.

ILLUSION APPARATUS.

1,310,707.

Specification of Letters Patent. Patented July 22, 1919.

Application filed January 28, 1919. Serial No. 273,634.

To all whom it may concern:

Be it known that I, JOHN LIPINSKI, a citizen of the United States, residing at Leavenworth, in the county of Leavenworth 5 and State of Kansas, have invented a certain new and useful Improvement in Illusion Apparatus, of which the following is a specification.

My invention relates to improvements in 10 illusion apparatus.

The object of my invention is to provide a novel illusion apparatus which is adapted to mystify and afford entertainment and in which a performer, although not in a 15 chamber containing water, appears to an observer to be submerged and to live and breathe in the water as in air.

The novel features of my invention are hereinafter fully described and claimed.

20 In the accompanying drawing which illustrates the preferred embodiment of my invention,

Figure 1 is a perspective view partly broken away of my improved apparatus, a 25 performer being shown in the lower chamber.

Fig. 2 is a vertical sectional view of the same with the performer eliminated.

Fig. 3 is an enlarged fragmental vertical 30 sectional view showing a portion of one of the side walls of the casing and a portion of the transparent partition.

Similar reference characters designate 35 similar parts in the different views.

I provide a casing having side walls provided with vertical upper portions 1, preferably lined with sheet metal 2. The portions 1 rest upon the upper edges of downwardly and outwardly inclined lower portions 3 of the side walls.

Extending horizontally between the side walls of the casing and dividing the latter into two chambers 4 and 5, disposed one above the other, is a transparent partition 6, preferably of clear plate glass. As shown in Fig. 3, the glass plate 6 extends between the upper portions 1 and lower portions 3 of the casing, and is held clamped by horizontal plates 7, secured to the portions 1 by vertical screws 8, against the sheet metal lining 2, which bears against the upper side and outer edges of the glass plate 6. If desired, cement 9 may be inserted between the lining 2 and the partition plate 6.

The lower chamber 5 is provided with a

bottom 10, on which may be placed earth or sand 11 so as to simulate a marine view, such as the bottom of a stream or other body of water.

In order to heighten the illusion, I provide means for simulating a water plant, which, as viewed from above, appears to have root in the sand 11 and to extend therefrom upwardly into the water in the chamber 4. Such means comprises one or more artificial plant stems 12, the lower ends of which are cemented or otherwise attached to the upper side of the transparent plate 6, and artificial plant stems 13 having their lower ends embedded in the sand 11 and their upper ends attached to the under side of the glass plate 6 in vertical alinement respectively with the stems 12.

To an observer looking downwardly 75 through the water, the stems 12 and 13 appear to be continuous, and present the appearance of a plant rooted in the sand 11 and extending up into the water in the upper chamber.

In order to make the illusion complete, I provide means for ruffling the surface of the water. This may be effected in any suitable manner, as by means of water dripping from a supply pipe 14, which is arranged so as to discharge into the upper chamber 4 above the level of the water therein. The pipe 14 may be provided with a controlling valve 15 by means of which the amount of water discharged into the 80 chamber 5 may be regulated.

The casing is preferably provided near the upper edge thereof with an overflow pipe 16.

One of the side portions 3 is removable 95 so as to permit entrance into and egress from the lower chamber 5 of the performer 17.

In the operation of my invention, the performer in the absence of and unknown to the 100 audience, enters the chamber 5. This chamber may be of any desired height and is large enough to enable the performer to assume different postures and to simulate swimming or other movements. The people 105 in the audience in looking downwardly through the ruffled surface of the water do not see the glass plate 6, so that the performer appears to be immersed in the water, this illusion being made complete by reason 110 of the fact that the stems 12 and 13 of the plant appear to extend continuously from

the sand 11 upwardly into the water, the break between the stems where they are attached to the glass plate 6 not being visible to any one looking downwardly through the water.

The performer may breathe, eat, smoke and do other acts which cannot be done by a person wholly immersed in water. To the audience, it appears that these acts are performed by the person while being immersed in the water, thus mystifying and entertaining the audience.

I do not limit my invention to the structure shown and described, as modifications, 15 within the scope of the appended claims, may be made without departing from the spirit of my invention.

What I claim is:—

1. In an illusion apparatus, a casing having opaque side walls, and a transparent horizontal partition extending between said side walls and forming two chambers, one above the other, the upper chamber being adapted to contain water, and the lower 25 chamber being adapted to receive a person, who, when in the lower chamber, is visible from above through the water and transparent partition, and two devices in said chambers respectively disposed in vertical 30 alignment with their adjacent ends secured respectively to the upper and lower sides of said partition, said two devices jointly simulating the stem of a plant.

2. In an illusion apparatus, a casing having opaque side walls, and a transparent

horizontal partition extending between said side walls and forming two chambers, one above the other, the upper chamber being adapted to contain water, and the lower chamber being adapted to receive a person 40 who is visible from above through the water and transparent partition, the lower chamber having a bottom simulating a marine view, and means in said two chambers and attached to the upper and lower sides of said partition simulating a plant which, apparently, as viewed from above, extends continuously from the bottom of the lower chamber into the water of the upper chamber.

3. In an illusion apparatus, a casing having opaque side walls, and a transparent horizontal partition extending between said side walls and forming two chambers, one above the other, the upper chamber being 45 adapted to contain water, and the lower chamber being adapted to receive a person who is visible from above through the water and transparent partition, the lower chamber having a bottom simulating a marine view, means in said chambers attached to and separated from each other by said partition simulating a plant which, apparently, as viewed from above, extends continuously 50 from the bottom of the lower chamber into the water of the upper chamber, and means for ruffling the surface of the water.

In testimony whereof I have signed my name to this specification.

JOHN LIPINSKI.
